UNITED STATES PATENT OFFICE.

EUGENE FRIEDELAENDER, OF BRADDOCK, PENNSYLVANIA.

INSULATOR.

1,111,570.

Specification of Letters Patent. Patented Sept. 22, 1914.

Application filed March 22, 1913. Serial No. 756,185.

To all whom it may concern:

Be it known that I, EUGENE FRIEDELAENDER, a citizen of the United States, residing at Braddock, in the county of Allegheny and State of Pennsylvania, have invented a new and useful Insulator, of which the following is a specification.

My invention relates to insulators employed in supporting electric conductors for electric railways, traveling cranes, and like apparatus, and while not restricted to such use, more particularly relates to the construction and arrangement of third rail insulators used with electric railways employing a third rail.

One object of my invention is to provide a strong and durable insulator of simple construction and having novel means whereby the insulator is applied for use in securing electric conductors, such as third rails, in operative position on the railway track crane, or crane runway, with which the insulators are used.

Another object of my invention is to provide an insulator having improved means whereby the possibility of loss of electrical energy is avoided and overcome, and liability of grounding or short-circuiting in all sorts of weather is lessened and prevented.

Still further objects of the invention will become apparent as the invention is more fully described and claimed hereinafter.

Referring to the drawings forming part of this specification, Figure 1 is an end elevation showing an insulator as constructed and arranged in securing the third rail of an electric railway in position upon a metal cross tie, in accordance with my invention. Fig. 2 is a longitudinal side elevation of the insulator shown in Fig. 1. Fig. 3 is a plan showing the insulator construction of Figs. 1 and 2.

In the accompanying drawings, the numeral 2 designates a metal cross tie of I-beam form, having a metal base or chair 3 secured thereto by means of clips 4 and fastening bolts 5.

The upper face of the chair 3 has upwardly extending flanges or lugs 6 positioned on opposite sides and at diagonal corners thereof which are arranged to embrace the sides of the insulating body 7. This body of insulating material preferably is formed of salt glazed porcelain, although fiber, wood or other suitable material may be substituted therefor when desired. Transversely extending registering holes are pro-

vided in the lugs 6, 6, and the insulating body 7 for the fastening bolts 8, 8, by which the insulating body is secured to the chair 3.

The opposite sides of the insulating material 7 are provided with outwardly projecting flanges or ribs 9 forming skirts which increase the surface over which moisture must creep or travel in order to form a ground. The ends of the insulation, being protected by the base of the T-head third rail forming the conductor, do not need this protection and for that reason do not have the skirts, although they may be provided when found necessary or desirable.

Surmounting the insulator 7 is a metal cap 10 having downwardly projecting flanges or lugs 11, 11, embracing the sides of the insulator, these lugs being positioned on opposite sides and diagonally opposite corners of the cap 10, and the upper face of the cap 10 has inwardly extending hook flanges 12, 12, positioned on the same diagonally opposite corners thereof and arranged to engage the flanges of the third rail 13 and secure the third rail 13 in position on the cap 10. Registering openings or holes are provided in the downwardly extending flanges 11, 11, and the upper portion of the insulating body 7 through which fastening bolts 14 extend to secure the cap 10 in position on the body of insulating material 7.

The cap 10 is made of such length and the hook flanges are positioned thereon in such manner as will make the shortest distance between the adjoining corners of the diagonally opposite hook flanges 12, 12, slightly greater than the overall width of the base flanges of the third rail 13, so as to permit the third rail to be inserted in place between the hook flanges, while positioned angularly relative thereto as indicated by the dotted lines in Fig. 3, and cause the hook flanges to overlap the flanges 13 and secure the third rail in position on the insulator when in the relative positions shown in full lines in the drawings.

By means of the construction shown the removal of the bolts 8 and 14 and the provision of the flanges 6 and 11 on diagonally opposite corners of the base 3 and cap 10, enables the body of insulating material 7 to be removed from and replaced in position between the chair or base 3 and the third rail 13 without any relative disarrangement of the third rail as erected in place on the cross ties 2 of the electric railway.

While the apparatus has been shown as

applied for use and secured in place on the metal cross ties of electric railways, the insulator may be employed with wooden ties and with electric traveling cranes, ore 5 bridges, gantries, and laying car tracks, and to other uses in securing the third rails or electric conductors in operative position by making suitable changes in the form of the chair or base 3 supporting the body of insulating material.

The advantages of my invention will be apparent to those skilled in the art.

Modifications in the construction and arrangement of the parts may be made without departing from my invention as defined in the appended claims.

I claim:—

1. In an insulator for electric conductors, the combination with a conductor and a 20 relatively fixed metal chair having upwardly extending lugs on diagonally opposite corners thereof, of a metal cap having conductor engaging hook flanges on its upper face and downwardly extending lugs 25 on diagonally opposite corners thereof, a body of insulating material between the chair and cap and embraced by the lugs on the said chair and cap, said insulating material having bolt holes therethrough 30 registering with holes in said lugs and bolts fastened in the registering holes to secure the insulating material to the chair and cap, the lugs on the cap being located on the diagonally opposite corners diagonally 35 opposite the lugs on the chair to permit the insertion and removal of the insulation without relative disarrangement of the conductor and chair.

2. In an insulator for electric conductors, 40 the combination with a conductor and a relatively fixed metal chair having upwardly extending lugs on diagonally opposite corners thereof, of a metal cap having conductor engaging hook flanges on its upper 45 face and downwardly extending lugs on diagonally opposite corners thereof, a body of insulating material between the chair and cap and embraced by the lugs on the said chair and cap, said insulating material having bolt holes therethrough registering with 50 holes in said lugs and bolts fastened in the registering holes to secure the insulating material to the chair and cap, the hook flanges on the cap being located on diagonally 55 opposite corners of the insulating material from the lugs on the chair to permit the insertion and removal of the insulation and cap without relative disarrangement of the conductor and chair.

60 3. In an insulator for electric conductors, the combination with a conductor and a relatively fixed metal chair having up-

wardly extending lugs on diagonally opposite corners thereof, of a metal cap having conductor engaging hook flanges on its upper face and downwardly extending lugs on diagonally opposite corners thereof, a body of insulating material between the chair and cap and embraced by the lugs on the said chair and cap, said insulating material having bolt holes therethrough registering with holes in said lugs and bolts fastened in the registering holes to secure the insulating material to the chair and cap, the lugs and the hook flanges on the cap being located on diagonally opposite corners of the insulating material from the lugs on the chair to permit the removal and insertion of the insulation of the cap without relative disarrangement of the conductor and chair.

4. A third rail insulator comprising in combination a metal chair, a body of insulating material removably mounted on the chair and having bolt holes therein, a metal cap surmounting the insulating material having integral rail engaging hook flanges thereon whereby the body of insulating material is fastened to the third rail, and means for detachably securing the insulating material and cap on said chair to permit the removal and replacement thereof, said means including lugs on two diagonally opposite corners of the chair and the cap embracing the body of insulating material, and securing bolts in the registering holes in 95 said lugs and insulating material.

5. In a third rail system the combination with a third rail and cross-tie, of an insulator for fastening the rail to the tie, said insulator comprising a metal chair fixed to 100 the tie, a body of insulating material removably mounted on said chair and having transversely extending bolt holes therein, and a metal rail securing cap surmounting and fastened to the insulating material, upwardly projecting lugs on the metal chair embracing the sides of the insulating material and having bolt holes therein registering with transversely extending holes in the insulating material and fastening bolts 105 extending through the registering holes to secure the insulating material to the chair, said lugs being positioned on two diagonally opposite corners of the chair to permit removal and replacement of the insulating material without relative disarrangement of the assembled cross-tie and third rail.

In testimony whereof, I have hereunto set my hand.

EUGENE FRIEDLAENDER.
